CLAIM

The ornamental design for an ammunition carrier for firearm magazine loader, as shown and described.

DESCRIPTION

FIG. 1 is a front perspective of a first embodiment of an ammunition carrier for firearm magazine loader of our new design;

FIG. 2 is a front elevation of the ammunition carrier;

FIG. 3 is a top view of the ammunition carrier;

FIG. 4 is a rear elevation of the ammunition carrier;

FIG. 5 is a bottom view of the ammunition carrier;

FIG. 6 is a front elevation of a second embodiment of an ammunition carrier for firearm magazine loader of our new design;

FIG. 7 is a top view of the ammunition carrier of FIG. 6;

FIG. 8 is a rear elevation of the ammunition carrier; and,

FIG. 9 is a bottom view of the ammunition carrier.

Features forming no part of the claimed design are illustrated in broken lines.

The right and left side elevations of the first embodiment of the ammunition carrier form no part of the claimed design.

The right and left side elevations of the second embodiment of the ammunition carrier form no part of the claimed design.
